UNITED STATES PATENT OFFICE.

WILLIAM GARVIE HALL, OF HONOLULU, TERRITORY OF HAWAII.

MACERATION DISTRIBUTOR FOR SUGAR-CANE MILLS.

Application filed February 13, 1923. Serial No. 618,814.

To all whom it may concern:

Be it known that I, WILLIAM G. HALL, a citizen of the United States, residing at Honolulu, in the Territory of Hawaii, have 5 invented certain new and useful Improvements in Maceration Distributors for Sugar-Cane Mills; and I do hereby declare the following to be a full, clear, and exact description of the invention, such as will enable others skilled in the art to which it 10 pertains to make and use the same.

The invention relates to an improved device for receiving and distributing the water or the admixture of water and juice employed for the purpose of macerating the bagasse as it passes from one mill to the next in the ordinary course of extraction of the sugar juice or sucrose from the cane in a multiple mill plant. To this end the invention 15 comprises a rotary cylinder or drum provided with a series of longitudinal troughs or pockets on its peripheral surface, said cylinder being adapted to be mounted above and transversely of the intermediate conveyor between successive sugar cane mills, the troughs or pockets receiving the macerating liquid from a suitable supply pipe and delivering the same uniformly over the bagasse as the cylinder rotates.

30 The invention is illustrated in the accompanying drawings in which:—

Fig. 1 is a diagrammatic end view of a 3-roll sugar cane mill showing the maceration distributor applied thereto.

35 Fig. 2 is a transverse vertical section through the maceration distributor.

Fig. 3 is a longitudinal vertical section through one end of the distributor.

In the extraction of sucrose or sugar juice 40 from cane it is customary to employ a series of mill units, a typical plant including a 2-roll crusher and four 3-roll mills with intermediate conveyors for the bagasse between the successive units. In order to effectively extract the juice as the latter is expressed by the rolls, it is found necessary 45 to supply macerating water or an admixture of water and juice to the bagasse as the latter passes through certain of the mills. A

50 typical application of maceration to a mill of this type is to apply water ranging from 10% to 50% of the weight of the juice to the bagasse after it leaves the third mill in a four-mill train, which water mixes with the bagasse and when pressed in the fourth or 55 last mill carries with it a certain amount of

sucrose, which would otherwise be lost. The juice from the fourth mill, which is very diluted, is returned as maceration water onto the bagasse between the second and third 60 mills, and the juice from the third mill is returned as maceration water to the bagasse between the first and second mills.

Various devices have been proposed for distributing the maceration liquid to the bagasse but, owing to the fact that the juices from the last mills in the train contain considerable cushcush or finely divided cane fibre, it has been found difficult to effect a uniform distribution of the macerating medium over the bagasse as the latter is carried from one mill to the next by the intermediate conveyors. It has been attempted to overcome the difficulty by straining the cushcush from the juices so that the latter might be 70 supplied or distributed over the traveling bagasse. The present invention is intended to obviate the necessity of straining the juices, but, nevertheless, to procure a uniform distribution of the maceration liquid 75 and the cushcush admixed therewith over the bagasse so as to insure a maximum extraction of the sucrose from the cane. The proposition of returning the juice, together with the cushcush, from a mill later in the 80 series to the bagasse entering a mill in advance is not novel per se, but, so far as applicant is advised, the apparatus to effect this result have signally failed, because of the inability to effect an equable distribution 85 of the maceration liquid and cushcush over the bagasse.

The present invention provides a thoroughly efficient, simple, cheap, and sanitary device for effecting this desirable object, as 90 will be evident from the description and operation thereof in connection with the annexed drawings.

Referring to the drawings, 1 represents a typical 3-roll mill such as is commonly 100 employed in extracting the juice from sugar cane. The crushed cane or bagasse is delivered by the mill 1 to a conveyor 2, which leads to the succeeding mill in the series. Mounted above and transversely of the conveyor 2 is a distributing cylinder or drum 3, which constitutes the basis of the present invention. Said drum comprises a central cylinder 4 provided with end flanges 6 and intermediate longitudinal ribs or webs 5, 110 which are preferably disposed radially to the axis of the cylinder and form, with the

surface of the cylinder and the end flanges, 6, a series of elongated troughs or pockets, adapted to receive the admixture of maceration liquid and cushcush from supply pipe 10. The cylinder is rotated by means of a chain and sprocket drive, such as 12, which connects the shaft 7, of the distributor with the shaft of the top roll of the mill, as illustrated in Fig. 1. It will be noted that, as the distributing cylinder rotates above the traveling bagasse on the conveyor 2, the macerating liquid and cushcush will be fed into the elongated trough-like elements of the distributing cylinder from the feed pipe 10, and immediately spreads evenly throughout the length of the receiving trough or gutter. As the cylinder continues to revolve, the cushcush laden liquid overflows the edge of the trough and is distributed in an even sheet or stream over the bagasse on the conveyor 2. As the troughs or pockets are filled and emptied, successively, it will be apparent that a substantially uniform supply of maceration liquid will be delivered to the bagasse on the conveyor below the distributor, and the presence of cushcush will in no wise adversely affect this uniform distribution.

It will be particularly noted that the distributor is exceedingly simple in construction, efficient in operation in that it effects uniform distribution of the maceration liquid under all conditions of operation, is not liable to damage or deterioration in that it involves no parts to be clogged up by the accumulation of cushcush, and is en-

tirely sanitary, capable of being easily cleaned and kept clean, which is a vital consideration in this particular art.

What I claim is:—

1. A maceration distributor for sugar cane mills, comprising a rotary cylinder having on its surface a series of longitudinal troughs, and means for supplying the maceration material to said troughs. 40

2. A maceration distributor for sugar cane mills, comprising a rotary cylinder having peripheral end flanges and radial ribs connecting said flanges to form longitudinal troughs on the surface of said cylinder, and means for supplying the maceration material to said troughs. 45 50

3. The combination of a sugar cane mill, a conveyor for feeding the bagasse to the mill, a maceration distributor, comprising a rotary cylinder having on its surface a series of longitudinal troughs extending transversely of and above the conveyor, and means for supplying the maceration material to said troughs. 55 60

4. The combination of a sugar cane mill, a conveyor for feeding the bagasse to the mill, a maceration distributor, comprising a rotary cylinder having peripheral end flanges and radial ribs connecting the flanges to form troughs on the surface of said cylinder, said distributor mounted transversely of and above the conveyor, and means for supplying the maceration material to said troughs. 65 70

In testimony whereof I affix my signature.
WILLIAM GARVIE HALL.
